UNITED STATES PATENT OFFICE.

EDWIN GEBHARDT, OF NORWOOD, OHIO.

FOLDING SEAL-STAMP.

1,122,903.

Specification of Letters Patent. Patented Dec. 29, 1914.

Application filed March 24, 1913. Serial No. 756,341.

To all whom it may concern:

Be it known that I, EDWIN GEBHARDT, a citizen of the United States, and a resident of the city of Norwood, in the county of 5 Hamilton and State of Ohio, have invented a certain new and useful Folding Seal-Stamp, of which the following is a full, clear, and exact description, reference being had to the accompanying drawings, forming 10 a part of this specification.

The object of my invention is to provide a charm for the watch chain or key ring which operates both as a cigar cutter and as a seal, and this I accomplish by that certain 15 construction and arrangement of parts to be hereinafter specifically pointed out and claimed.

In the drawings, Figure 1 is a front elevation of my device ready for use as a cigar 20 cutter. Fig. 2 is a side elevation, taken at right angles to Fig. 1. Fig. 3 is a side elevation of the device ready for use as a seal. Fig. 4 is a top plan view of the same. Fig. 5 is a central vertical section of the stamp 25 opened for use, with part of the cigar cutter plate cut away.

1 and 2 are the two segments of a seal, made of suitable material, attached together by the hinge 3 and bearing on their combined surfaces a character, initial, or any 30 desired design, to be used as a seal. On the inner side of the seal, and preferably located well away from its center, are the hinge joints 4 and 5, with their axes parallel to 35 the axis of the hinge 3, which connect to the segments of the seal the plates 6 and 7. These plates are of restricted length suitable for the purpose desired, but necessarily long 40 enough to accommodate the parts of the cigar cutter as hereinafter described. They are joined together at their far ends by the hinge joint 8 parallel to the joints 3, 4 and 5, and the pintle 9 of this joint carries a ring or bow 10.

45 The construction above detailed is that of my seal alone. Its method of operation is clear. To fold up the seal into the position shown in Fig. 2, the operator flexes the four hinged joints 3, 4, 5 and 8, which 50 are parallel to each other. To open it into the position shown in Fig. 3, he merely reflexes the said hinges.

The cigar cutter is formed entirely in the side plate 6, the plate 7 merely being

provided with an aperture 11, in order not 55 to interfere with the operation of the cutter when the device is in closed position.

On and parallel to plate 6, is suitably secured an additional plate 12. Near the top of these plates is located an aperture 60 13 for the introduction of a cigar to be cut. Rotatably mounted on a pin 14, between the two plates 6 and 12, is the arm 15 which carries the cutter knife 16. On the back of the arm 15 is a thumb plate 17. Mounted 65 on the pin 18, located above the cigar hole, is a spring 19, which bears against the slightly rounded surface 20 on the end of the cutter arm. This spring serves to force the cutter arm to swing away from the 70 plates 6 and 12 as soon as the arm is released, and a means of holding the cutter and its arm inside of the two plates is provided as follows: A small plate 21 is mounted 75 between the plates 6 and 12, just below the cigar hole, having a blunt tooth 22. A spring 23 bears against the base of the plate and tends to force the plate and tooth upward. The cutter blade has a notch 24 on its lower edge to receive the tooth 22 when 80 the cutter is in closed position. To release the cutter, it is necessary to push down the plate 21, and for doing this I supply the pin 25 attached to the plate and guided by a slot (not shown) in the plate 6. Upon de- 85 pressing the pin 25 and releasing the knife, the spring 19 throws open the cutter. A cigar tip may then be inserted in the hole 13, and with the free hand the operator can push in the cutter by pressing on the 90 thumb plate 17. It is thus that I provide a compact and efficient cigar cutter and seal.

The entire article is compact and strong and folds into a neat and attractive shape. It can be made of precious metal, or of the 95 baser metals, and can do combined duty as a tool and a piece of jewelry. The bow 10 serves to attach it to a watch chain or key ring. Instead of the cutter shown, a knife blade may be substituted, as will be readily 100 understood.

Having thus described my invention, what I claim as new and desire to secure by Letters Patent, is:—

1. A new article of manufacture comprising 105 a head of two hinged portions for a seal, and a handle portion comprising side plates adapted to be hinged to said portions with

the hinges so located that the seal will fold outwardly, with said side plates hinged together at their outer ends.

2. A new article of manufacture comprising a head of two hinged portions for a seal, a handle portion comprising side plates adapted to be hinged to said portions, said side plates hinged together at their outer ends with the hinges so located that the seal will fold outwardly, and a bow carried by the pintle of the last named hinge, with the side plates of a length suitable for mounting a tool.

3. A new article of manufacture comprising a head of two hinged portions for a

seal, a handle portion comprising side plates adapted to be hinged to said portions, said side plates hinged together at their outer ends with the hinges so located that the seal will fold outwardly, and a bow carried by the pintle of the last named hinge, with the side plates of a length suitable for mounting a tool.

EDWIN GEBHARDT.
